FEEDING MECHANISM FOR SEWING MACHINES

Anthony J. Matuzas, Union, N. J., assignor to The Singer Manufacturing Company, Elizabeth, N. J., a corporation of New Jersey

Application July 30, 1952, Serial No. 301,644

9 Claims. (Cl. 112—210)

1

This invention relates to sewing machines and more particularly to improvements in feed-dog throw-out devices especially adapted for use with family-type sewing machines. Feed-dog throw-out devices are designed to inactivate the work-feeding mechanism of sewing machines when it is desired to use the sewing machine for darning, embroidering and other similar operations, and to reactivate the feeding mechanism when the machine is to be used for ordinary sewing operations.

The present invention is adapted for use with the feed-dog throw-out device which is the subject of a patent application of Josef F. Palme and Jacob B. Benzing, Serial No. 222,616, filed April 24, 1951, and the present invention has for its primary object the provision of an improved feed-dog throw-out device.

Another object of the invention is to provide a feed-dog throw-out device which is easy to operate and which is positive in its action.

A further object of the invention is to provide a feed-dog throw-out device which when adjusted for feeding will always raise the feed-dog to the same elevation.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art. In the drawings,

Fig. 1 is a vertical sectional view of a portion of a sewing machine embodying the invention,

Fig. 2 is a bottom plan view of the portion of the sewing machine shown in Fig. 1, and

Fig. 3 is a perspective view, as seen from above, of certain of the elements illustrated in Figs. 1 and 2.

In the embodiment of this invention selected for illustration, the numeral 11 indicates the substantially rectangular bed-plate or base of the sewing machine providing on its upper side a work-supporting plate 12 and having, formed integral with its under side, downwardly extending front and rear walls 14 and 16, and end walls 17 and 18, forming a box-like enclosure, of which the downwardly facing opening is normally closed by a bottom cover-plate 19 held in place by a nut (not shown).

An upstanding hollow standard 21 rises from the bed 11 and at its upper end the standard carries an overhanging bracket-arm (not shown) of which the free end carries the usual reciprocating needle-bar 24 and the presser-bar 25.

The bracket-arm rotatably supports an unshown main drive-shaft which operates the reciprocating needle-bar 24, in a known manner, and this same drive-shaft in a manner shown and

described in patent application of Wilbur J. Peets, Serial No. 774,597, filed September 17, 1947 (now Patent No. 2,617,375), drives a loop-taker shaft 27, which in turn drives a loop-taker 28 arranged to cooperate with a suitable thread-carrying needle 29 in the formation of stitches. Since the stitch-forming mechanism forms no part of the present invention, further illustration and description thereof is deemed unnecessary. If desired the stitch-forming mechanism may be constructed and operated in a manner similar to that disclosed in the United States patent of Herbert J. Goosman, No. 2,063,841, dated December 8, 1936.

15 The work-support 12 is provided with a throat-plate 31 having feed-slots 32 through which operates a serrated feed-dog 34 secured by screws 37 on one end of a long feed-bar 36. At its rearward end, the feed-bar 36 is pivotally connected, as at 38, to the upper end of a pair of feed-advance rockers 39 extending upwardly from a feed-advance rock-shaft 41 journaled on suitable pintles, of which one is shown at 42. Also, a feed-lift rock-shaft 44 is journaled on pintles, 20 of which one is shown at 43. Suitable oscillatory movements are given to the feed-advance rock-shaft 41 and the feed-lift rock-shaft 44 by any known means such, for example, as disclosed in Patent No. 2,617,375, supra.

25 30 The feed-bar 36 is provided with a depending lug 47, of which the lower end carries a horizontally extending pin 48 that pivotally mounts the lower end of an upwardly extending link 49. The upper end of the link 49 is pivotally connected

35 by a pin 51 to one arm 52 of a horizontally extending lever 53, having a central hub 54 freely journaled on the feed-lift rock-shaft 44. The hub 54 is provided with an annular recess 56 concentric with the shaft 44. The recess 56 accommodates a helical spring 57 having one end anchored in a hole 58 formed in the lever 53 and having its other end anchored in a hole 59 provided in a flange 61 formed integral with the feed-lift rock-shaft 44, the flange 61 being located adjacent to one side face of the lever 53 and thus preventing the lever 53 from movement longitudinally of the feed-lift rock-shaft 44. The lever 53 is held 40 from movement in the other direction longitudinally of the shaft 44, by a spring wire clip 62 seated in a groove in the shaft 44. Another arm 63 of the horizontally extending two-armed lever 53 is apertured by a horizontally extending funnel-shaped hole or clearance aperture having a cylindrical portion 64 and having at its end nearest the wall 17 and thus remote from the crank-arm 68, hereinafter mentioned, a concave frusto-conical countersink or seat portion 66 for seating a convex frusto-conical self-centering member 121 presently to be described.

45 50 55 60 It will be noted that the two arms 52 and 63 of the lever 53 extend horizontally on opposite

sides of the feed-lift rock-shaft 44, the arm 52 extending toward the loop-taker shaft 27 in the front of the sewing machine bed, and the arm 63 extending toward the feed-advance rock-shaft 41 in the rear of the bed. It will also be noted that the lever 53 is of uniform thickness as measured in the direction of the axis of the feed-lift rock-shaft 44. Also the seating members 66 and 121 are both of symmetrical, frusto-conical form, and the cylindrical portion 64 and the frusto-conical portion 66 are concentric.

The hereinbefore mentioned feed-lift rock-shaft 44 carries a horizontally extending crank-arm 68 adjacent to and formed integral with the flange 61. The arm 68 is provided with a horizontally extending cylindrical threaded hole 69. In order to limit the downward movement of the feed-dog 34, there is provided a bracket 83, which is held to a boss of the base 11 by a screw 82. The bracket 83 has a threaded hole and thereby carries an adjustable stop-screw 86 of which the upper end (not shown) may be engaged by the lower surface of the arm 52. The previously described mechanism is substantially the same as the mechanism which formed the subject of the patent application Serial No. 222,616 supra.

The present invention is concerned primarily with a novel and improved means for selectively connecting and disconnecting the integrally formed flange 61 and crankarm 68 with the arm 63 which is apertured by the hole 64—66 of which, as stated, one portion 64 is cylindrical and the other portion 66 is frusto-conical. This connecting means comprises a cylindrical stem or screw 101, of which the major portion is externally threaded as at 102. A small head-end portion 103 of the stem is unthreaded and this head portion 103 is provided with a screw driver slot 104. A thumb-nut 105, having a knurled head 106 and a shank 107, is provided with a concentric bore 108. The major portion of the bore 108 of the thumb-nut 105 is internally threaded as at 109, however, the portion 112 of this bore adjacent the head 106 is unthreaded, smooth and counterbored so that the unthreaded head 103 of the screw 101 may, as best shown in Fig. 2, enter the bore 108 for a short distance. The shank 107 of the nut 105 is split longitudinally by a saw cut 113. The head of the thumb-nut 105 is also provided with a recessed screw driver slot 114.

A hollow sleeve 116, having an enlarged end or centering head 117 and a stem 118, is provided with an unthreaded axial, concentric bore 119 coextensive with the sleeve. The enlarged end 117 has an out-facing convex frusto-conical surface or centering member 121 having the same slope as the concave frusto-conical countersink 66 hereinbefore described. When the threaded portion 102 of the stem 101 is screwed into the threaded hole 69, as hereinafter described, a lock-nut 124 is screwed on the end of the stem 101 thus securing the stem 101 to arm 68. With this arrangement, the sleeve 116 is both rotatably and slidably mounted on the screw 101, and the thumb-nut 105, due to the threads 102 and 109, may be moved toward or away from the sleeve 116, thus making it possible selectively to seat the frusto-conical centering member 121 in the countersink 66 or to release the centering member 121 from the countersink 66. In this connection it should be noted that, due to the unthreaded head 103 of the screw 101, the thumb nut 105 cannot be removed from the head end

103 of the screw 101, and thus the nut 105 must be screwed on the stem 101 before the stem 101 is screwed into the hole 69. Also, because of the slit 113, the shank 107 of the thumb-nut 5 105 can be adjusted to hold the thumb-nut 105 in any selected position thus assuring that the arms 53 and 61—68 will either remain connected or disconnected depending on the setting of the thumb nut 105.

10 The operation of the mechanism is as follows. When it is desirable to use the sewing machine for darning or embroidering, the feed-dog 34 is depressed below the upper surface of the throat-plate 31 by grasping the thumb-head 106 and turning the thumb-nut 105 from the position shown by solid lines in Fig. 2 to the position therein shown by dotted lines. This releases the frusto-conical centering member 121 from the countersink 66 and breaks the connection 15 between the arm 63 of the lever 53 and the arm 68 of the rock-shaft 44. Since the external diameter of the screw 101 is much less than the internal diameter of the hole 64, the lever 53 is free to move independently of the feed-lift rock-shaft 44 and its integral arm 68. Under these circumstances, the spring 57 biases the lever 53 20 to turn clockwise as seen in Fig. 1, until the lower surface of the arm 52 of the lever 53 is stopped by the upper end (not shown) of the screw 86. 30 This lowers the arm 52, the pin 51 and consequently lowers the link 49, the pin 48 and the depending lug 47, with the result that the feed-dog 34 is lowered below the upper surface of the throat-plate 31. Since the conical centering member 121 is disengaged from the countersink 66, the feed-lift rock-shaft 44, its integral arm 68, and the stem 101 are free to move without causing movement of the feed-dog 34. This 35 freedom of movement is fully described in the 40 hereinbefore mentioned patent application Serial No. 222,616.

When it becomes desirable to use the sewing machine to perform ordinary sewing operations, the thumb nut 105 by means of the thumb-head 106 is screwed from the dotted position shown in Fig. 2 to the position shown by solid lines. As this is done, the end 107a of the shank 107 engages the end 116a of the sleeve 116, and, as the sleeve 116 is pushed forward by the shank 50 107, the inclined surface 121 of the centering member 116 engages the frusto-conical countersink 66 with the result that as the thumb-nut 105 advances on the screw 101, the lever 53 is caused to move counter-clockwise (Fig. 1) about the shaft 44 against the bias of the spring 57, until the conical flange 121 becomes fully seated in the countersink 66. This always brings the feed-dog 34 to the proper height, because there is no chance of the member 121 sticking or binding 55 until full seating has been attained. When this is achieved, the screw 101 becomes concentric with the hole 64 and the lever 53 becomes clamped to the arm 68, the arm 52 of the lever 53 is raised from contact with the top of the stop-screw 86, and whenever the feed-lift rock-shaft 60 44 oscillates, the lever 53 moves therewith, causing the link 49 alternately to lift and lower the feed-bar 36, imparting rising and falling movements to the feed-dog 34. It should be noted that the 65 conical centering member 121 and the countersink 66 are of such size and shape as to easily and properly elevate the feed-dog 34 for ordinary seaming operations when the centering member 121 70 is caused to engage the seat 66.

Having thus set forth the nature of the invention, what I claim herein is:

1. In a sewing machine, a releasable connection for selectively connecting and disconnecting a feed-lift rock-lever with a crank-lever, each of said levers having a hole and one of said holes being a centering hole, comprising, a threaded-stem freely passing through said centering hole and fastened into said other hole; a hollow sleeve having an unthreaded longitudinal bore and a centering head for engaging said centering hole, said sleeve being carried on said threaded stem; and a thumb-nut screwed on said threaded-stem for moving said hollow sleeve.

2. In a sewing machine, a releasable connection for selectively connecting and disconnecting a feed-lift rock-lever having a conical hole, with a crank-arm having a threaded hole comprising, a threaded-stem freely passing through said conical hole and screwed into said threaded hole; a hollow sleeve having a longitudinal bore and a centering head for engaging said conical hole, said sleeve being slidably carried on said threaded stem; and a thumb-nut screwed on said threaded-stem for moving said sleeve.

3. In a sewing machine, a releasable connection for selectively connecting and disconnecting a feed-lift rock-lever having a funnel-shaped hole, with a crank-arm having a threaded hole comprising, a threaded-stem freely passing through said funnel-shaped hole and screwed into the threaded hole of said crank-arm, a hollow sleeve having an unthreaded longitudinal bore and a frusto-conical centering head for engaging said funnel-shaped hole, said sleeve being slidably carried on said stem; and a split thumb-nut screwed on said threaded-stem for engagement with said sleeve.

4. In a sewing machine, a releasable connection for selectively connecting and disconnecting a feed-lift rock-lever having a funnel-shaped hole, with a crank-arm having a threaded hole comprising, a threaded-stem freely passing through said funnel-shaped hole and screwed into the threaded hole of said crank-arm, said stem having a smooth head provided in its end with a screw-driver slot; a nut locking said stem to said crank-arm; a hollow sleeve having a longitudinal bore and a frusto-conical centering head for engaging said funnel-shaped hole, said sleeve being slidably carried on said stem; a thumb-nut having a split portion screwed on said stem for moving said hollow sleeve, said thumb-nut having a smooth bore to receive the smooth head of said stem.

5. A feed-dog throw-out mechanism for sewing machines including in combination a rock-shaft, a crank-lever carried by said rock-shaft, a lever pivoted on said rock-shaft, one of said levers being provided with a conical hole and the other lever being provided with a threaded hole, a feed-dog, means connecting one of said levers with said feed-dog, and a releasable connection selectively connecting and disconnecting said levers, said releasable connection comprising a threaded-stem freely passing through said conical hole and screwed into said threaded hole, a hollow sleeve having a longitudinal unthreaded bore and a centering head, and a thumb-nut screwed on said threaded-stem.

6. A feed-dog throw-out mechanism for sewing machines including in combination a rock-shaft, a crank-lever formed integral with said rock-shaft, a lever pivoted on said rock-shaft, one of said levers being provided with a funnel-

shaped hole and the other lever being provided with a thread-hole, a feed-dog, means connecting one of said levers with said feed-dog, and a releasable connection selectively connecting and disconnecting said levers, said releasable connection comprising, a threaded-stem freely passing through said funnel-shaped hole and screwed into said threaded-hole; a hollow sleeve having a longitudinal bore and a frusto-conical centering head, said sleeve being slidably carried on said stem, and said centering head adapted to enter said funnel-shaped hole; and a thumb-nut screwed on said threaded-stem.

7. A feed-dog throw-out mechanism for sewing machines including in combination a rock-shaft, a crank-arm formed integral with said rock-shaft and said crank-arm being provided with a threaded hole, a feed-dog, a lever pivoted on said rock-shaft and provided with a funnel-shaped hole having a cylindrical portion and a frusto-conical portion concentric with said cylindrical portion, means connecting said lever with said feed-dog, and a releasable connection selectively connecting and disconnecting said lever and said crank-arm, said releasable connection comprising, a threaded-stem freely passing through said funnel-shaped hole and screwed into the threaded hole of said crank-arm, a nut locking said stem to said crank-arm; a hollow sleeve having a longitudinal bore and a frusto-conical centering head, said sleeve being slidably carried on said stem; and a split thumb-nut screwed on said threaded-stem.

8. A feed-dog throw-out mechanism for sewing machines including in combination, a rock-shaft, a crank-arm formed integral with said rock-shaft and said crank-arm being provided with a threaded hole, a feed-dog, a lever pivoted on said rock-shaft and provided with a funnel-shaped hole having a cylindrical portion and a frusto-conical portion concentric with said cylindrical portion, means connecting said lever with said feed-dog, a releasable connection selectively connecting and disconnecting said lever and said crank-arm, said releasable connection comprising, a threaded-stem freely passing through said funnel-shaped hole and screwed into the threaded hole of said crank-arm, said stem having a smooth head provided with a screw-driver slot; a nut locking said stem to said crank-arm; a hollow sleeve having a longitudinal bore and a frusto-conical centering head, said sleeve being slidably carried on said stem; a thumb-nut having a split portion screwed on said stem and a smooth bore to receive said smooth head of said stem.

9. In a sewing machine, a releasable connection for selectively connecting and disconnecting a feed-lift rock-lever with a crank-lever, each of said levers having a hole and one of said holes being a centering hole, comprising a stem freely passing through said centering hole and having one end securely fixed into said other hole; a hollow sleeve having an unthreaded longitudinal bore and a centering head for engaging said centering hole, said sleeve being slidably carried on said stem; and a thumb member turnable on the free end of said stem and arranged to move said sleeve lengthwise on said stem.
